UNITED STATES PATENT OFFICE.

PATRICK B. DELANY, OF SOUTH ORANGE, NEW JERSEY, ASSIGNOR TO TELEPOST COMPANY, OF NEW YORK, N. Y., A CORPORATION OF MAINE.

AUTOMATIC TELEGRAPHY.

1,052,219.

Specification of Letters Patent.

Patented Feb. 4, 1913.

Original application filed December 29, 1908, Serial No. 469,804. Divided and this application filed April 27, 1911. Serial No. 623,602.

To all whom it may concern:

Be it known that I, PATRICK B. DELANY, a citizen of the United States, residing at South Orange, county of Essex, State of 5 New Jersey, and at Nantucket, county of Nantucket, State of Massachusetts, have invented a certain new and useful Improvement in Automatic Telegraphy, of which the following is a specification.

10 This invention relates to automatic telegraph receiving devices.

In the accompanying drawings: Figure 1 is a perspective view: and Fig. 2, a vertical central section.

15 The receiving drum m^2 has circumferentially and centrally thereof an inset band n of insulating material. The receiving stylus f' opposite this insulating band is to bear upon the chemically prepared receiving

20 tape that will travel in contact with the peripheral face of the drum,—that is with its peripheral surfaces m^3 , m^4 and n . The drum may be connected to earth or return circuit by a brush b bearing upon one of the side faces of the drum.

25 This application is a division of my application, No. 469,804, filed December 29, 1908.

I claim:

An automatic telegraph recorder comprising a contact drum having a circumferential groove, a band of insulating material seated in the groove and a recording finger located opposite the band of insulating material and between which and the peripheral surface of the drum the chemically prepared receiving tape is to pass.

30 In testimony whereof, I have hereunto subscribed my name.

PATRICK B. DELANY.
